UNITED STATES PATENT OFFICE.

ASA WILMOT, OF NEW HAVEN, CONNECTICUT.

IMPROVEMENT IN SAFETY-POCKETS.

Specification forming part of Letters Patent No. 40,528, dated November 3, 1863.

To all whom it may concern:

Be it known that I, ASA WILMOT, of the city and county of New Haven, and State of Connecticut, have invented a new and useful Improvement in Pockets; and I do hereby declare the following to be a full, clear, and exact description of the same, when taken in connection with the accompanying drawings, which form a part of this specification, in which—

Figure 1 is a front view. Fig. 2 is a top view of the mouth closed. Fig. 3 is a section on *x y*. Fig. 4 is a top view, mouth open.

Same letters of reference indicate like parts.

The object of my invention is to construct a pocket upon which the operations of the most skillful pickpocket will be unsuccessful; and it consists in closing the mouth of the pocket by means of an elastic band attached to a metal stay, in the manner of a bow and bow-string, so that the contents could not be taken therefrom without the knowledge of the wearer.

To enable others to make and use my improved pocket, I will proceed to describe my manner of so doing.

I make my improved pocket independent of the garment in which it is to be worn. Upon the upper edge of the inner side, A, I insert a stay of steel or similar material to hold the mouth of the pocket flat, and upon the opposite side or front, B, I insert an elastic cord or band, each end of which is fastened at or near the ends of the said metallic stay. The front I make full and shirr it upon the said elastic.

To attach the pocket to a garment I prefer to place it within a common pocket. I make eyes *a c* upon the metal stay, and by these in any convenient manner make my pocket fast

to the garment within the pocket thereof. The bag of the pocket hangs down within the said pocket and does not materially effect the same for other purposes. To open the mouth of my pocket to place anything therein or take therefrom the elastic must be expanded sufficiently for the purpose, as in Fig. 4. This requires so much force that other hands than the wearer's would cause so much strain upon the garments as not to permit its being done without his knowledge, and for the same reasons instruments could be used for the purpose of extracting the contents through the mouth of the pocket as may be and often is done from common pockets.

To prevent extraction of the contents by means of cutting the garments, I make the front of the pocket of two thicknesses of fabric, *d* and *b*. Between these I place a net-work of metallic chains, or their equivalents, as denoted by red lines, Fig. 1, and 2 3 4 in Fig. 3, and I place these chains so near together, or make the meshes so small, that, although the fabric be cut, the contents cannot be extracted therefrom, and thus I produce a pocket proof against the operations of the most skillful pickpocket.

Having thus fully set forth my invention, what I claim therein, and desire to secure by Letters Patent, is—

A pocket protected at its mouth, in the manner described, by an elastic cord or band, *e*, combined with a metallic stay, substantially as specified.

ASA WILMOT.
